UNITED STATES PATENT OFFICE

2,607,367

VALVE

Daniel Mapes, West Caldwell, N. J., assignor to
Specialties Development Corporation, Bloom-
field, N. J., a corporation of New Jersey

Application December 21, 1944, Serial No. 569,133

4 Claims. (Cl. 137—652)

1

This invention relates to valves, and particularly to valves of the pilot operated type.

In certain valves heretofore employed for controlling high pressure fluid media, such as carbon dioxide for fire extinguishing purposes, and other fluids for other applications, it has been customary to operate the main valves by the pressure media being controlled. In a valve of this type, the main valve is held closed by the pressure of the fluid media, and is opened by a pressure responsive device, such as a piston of larger area than the main valve member. The pressure media admitted to the piston cylinder, is controlled by a pilot valve member of small area and requiring less force for its operation than the main valve member.

It has also been usual, in a valve of this type, to provide the main valve with a pilot valve aperture which is controlled by the pilot valve member. A hollow main valve stem, which communicates with the pilot valve aperture, is connected to the piston for operating the main valve, and serves as a conduit for conducting the fluid pressure media to the piston, and as a means through which a pilot valve stem extends for operating the pilot valve member.

An object of the present invention is to provide a valve of the pilot type with only one stem, or one complete stem, such as the main stem, which operates both the pilot and main valve members, and to effect this result in a novel manner to very materially reduce the number of parts, to simplify the necessary retained parts, to reduce the amount of machining, and to render the valve more compact and an improvement generally in its field.

Another object is to provide a novel unit structure which is adapted to directly actuate a pilot valve and a main valve, as above mentioned, with minimum effort.

Another object is to adapt a single valve stem for successive movements, or continuous steps of substantially the same movement, whereby one movement, or step of the same movement, actuates a pilot valve for effecting a succeeding movement or step for actuating the main valve, as distinguished from entire movements or steps of separate stems.

A further object is to provide a device of the above indicated character which is simple and durable in construction, economical to manufacture, and effective in its operation.

A still further object is to provide a fire extinguisher embodying the present invention.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description, and is shown in the accompanying drawing, forming a part of the specification, wherein the single figure is a sectional view of a valve, embodying the invention, shown as secured to a container.

Referring to the drawing, there is shown the upper portion of a high pressure fluid media container 10, such as a cylinder for storing carbon dioxide adapted to serve as a fire extinguishing medium, having a valve or control head 12 secured thereto for controlling the discharge of the pressure media therefrom.

The container 10 has a neck 14 provided with an interior tapered screw thread 16. The control head 12 comprises a body or housing 18 provided with a lower inlet portion 20 cooperatively screw threaded into the neck 14, a main valve chamber portion 22 communicating with the inlet of the portion 20, and having a main valve seat 24 around the inner end 26 of a bore 28 extending from the chamber 22 to an outer end 30 of the bore constituting a recessed portion for receiving a cap 34 constituting a piston cylinder 35 and communicating with the exterior of the head through an opening 36 in the cap, as more fully will appear.

A bore 38, communicating with, and extending transversely to, the bore 28 through the head, and through a discharge conduit coupling 40, cooperates with the portion of the bore toward the chamber 22 therefrom to constitute an outlet conduit from the chamber. An interiorly screw threaded recessed portion 42 of the head body 18, communicating with the valve chamber 22 through ducts 44 and 46, is adapted to receive an excess pressure safety blowout disc 48, held in position by a gasket 50, and an anti-recoil discharge, screw plug 52.

A main valve member 54, in the chamber 22, comprises a cup like shell 56 having a bottom wall edge 58 defining a hole in the shell in which a bottom edge 60 of a core member 62 is disposed and peened outwardly for mounting the shell on the core. A yieldable body 64, constituting the direct sealing contact portion of the main valve member 54 for the valve seat 24, surrounds the core 62 in the shell 56 which has an

inwardly inclined upper side wall 66 slightly compressing the body 64 to hold the latter in place.

The core member 62 forms a pilot valve chamber 68 having an inlet defined by the edge 60 and including a pilot valve seat 70 around an outlet portion 72. Above the outlet portion 72, as shown, the core 62 has a portion 74 outwardly shaped to center the main valve member 54 in the bore 28 and having a recess 76 in which a hollow valve stem 78 longitudinally slidably fits with its lower end 80 normally spaced above a shoulder 82 of the core for engagement by the end 80, as will further appear.

A pilot valve member 86 in the chamber 68, has a short rod like part 88 projecting therefrom into the stem 78 for engagement by a pin 90 fixed to the stem. The pilot valve member 86 is normally biased into engagement with the seat 70 by the pressure media, and by a compression spring 92 resting on a sleeve 94 that is pressed fitted or otherwise secured to the core member in the pilot valve chamber 68.

The main valve member 54 is normally biased into engagement with the seat 24 by the fluid pressure, and by a compression spring 96 supported by a syphon tube 98, and surrounded by a tubular portion 108 of a member 102 which is screw threadably supported on the portion 20 and screw threadably supports the syphon tube 98.

The cap 34, constituting a cylinder for a piston head 104, or a chamber for other fluid pressure device, such as a bellows, is screw threadably mounted in the recess of the portion 30 against a washer 106 over a sealing gasket or packing gland 108 in a recess 110 of the body 18 around the bore 28. The inner end edge 112 of the cap 34 and the washer 106 form an annular space 114 communicating with a duct 116 in the body 18 and a duct 117 in the cup 34 for venting the lower or advance side of the piston 104.

The piston head 104 which, with the hollow stem 78 as its rod, constitutes a piston, is press fitted or otherwise secured to the stem over a shoulder 118 thereon, and has a gasket 120, or piston ring structure, in an annular peripheral gasket or ring seat thereof. The cap 34 carries a sealing gasket or packing gland 122 around the aperture 39 in an outer end wall 126 of the cap through which the stem 78 extends.

The stem 78 has a transverse inner partition 128 closing the bore thereof, adjacent to which a radial duct 130 constitutes a passageway whereby the stem constitutes a conduit for conducting the fluid from the chambers 22 and 68 to the cylinder cap 34 at the fluid pressure side of the piston head 104. Above the partition 128, the stem 78 is provided with a small longitudinal bore 132 communicating between transverse ducts 134 and 136 above and below the wall 126, respectively, and closed by an operating handle or knob 138, or by other means, such as a plug. A spring 140 between the handle 138 and the cap 34, normally maintains the stem 78 in the upper position shown. This structure normally provides a vent for the fluid pressure side of the piston, and closes this vent when the stem is manually thrust inwardly, by the handle 138 or otherwise, by placing the duct 134 in the sealing gasket or gland 122, when the stem is actuated to open the pilot valve. The outer end of the stem may be constituted otherwise than as shown for the relayed thrust action of remotely controlled actuating means.

In operation, with all of the parts disposed in the inactive non-discharging positions as

shown, a thrust on the stem 78, as by pushing the handle 138, causes the pin 90, at the inner end of the stem, to transfer this thrust to the rod 88 to unseat the pilot valve member 86, and 5 closes the vent duct 134. The pressure media then passes through the main valve member 54, by way of the pilot valve chamber 68, past the pilot valve seat 70, into the stem 78, past the rod portion 88 and the pin 90, along the stem 10 and through the duct 130 into the cylinder 34 at a position above, or at the fluid pressure side of the piston head 104. The latter is thereupon further thrust downwardly to carry with it the stem 78, whereby the lower end 80 of the latter engages the shoulder 82 to unseat the main valve member 54 for the release of the main discharge flow from the chamber 22 into the bore 28, and through the bore 38, and the coupling 40, to a conduit, such as a hose or a pipe.

During the above described action, the second, or piston operated thrust may so closely follow the initial thrust as to be manifested substantially as a continuation, or only a momentary interruption thereof, whereby an operator's hand or other means may follow through on the action. However, it is only necessary that the initial thrust be sufficient to open the pilot valve, which is all that is required of an actuator or other structure forming a part of the device.

From the foregoing description, it will be apparent that a novel main and pilot valve structure arrangement has been provided, which is simplified and rendered more economical and compact, as to number and complication of parts, 35 manufacture, reduction in size and other factors, and which is a substantial improvement in apparatus with which the invention is concerned.

As various changes may be made in the form, construction and arrangement of the parts herein, without departing from the spirit and scope of the invention, and without sacrificing any of its advantages, it is to be understood that all matter herein is to be interpreted as illustrative and not in any limiting sense.

I claim:

1. A valve comprising a housing having a valve chamber provided with an inlet, an outlet and a main valve seat intermediate said inlet and outlet, and having a piston chamber adjacent said valve chamber provided with aligned apertures at opposite ends thereof respectively extending from said piston chamber to said valve chamber and from said piston chamber to the exterior of said housing; a main valve member 50 formed with an inlet, an outlet and an intermediate pilot valve seat; a pilot valve member; a stem extending through said apertures; a piston in said piston chamber on said stem; and means on said stem for engaging said pilot valve member and said main valve member constructed and arranged to first effect unseating of said pilot valve member before engaging said main valve member to effect unseating thereof upon movement of said stem; said stem having a passage for establishing communication between said main valve member inlet and said piston chamber at the working side of said piston when said pilot valve is unseated, and said stem having a second passage normally establishing communication between the exterior of said housing and said piston chamber at the working side of said piston and constructed and arranged to shut off such communication when said stem is moved to unseat said pilot valve member.
2. A valve according to claim 1, including

spring means constructed and arranged for normally urging said stem out of engagement with said pilot valve member and said main valve member to place said second passage in communication with the exterior of said housing and thereby vent said piston chamber.

3. A valve according to claim 2, including spring means for urging said pilot valve member against its seat when said first mentioned spring means act to urge said stem out of engagement with said pilot valve member whereby communication between said main valve member inlet and said piston chamber is shut off.

4. A valve according to claim 3, including spring means for urging said main valve member on its seat.
